UNITED STATES PATENT OFFICE.

BASIL KAMENSKI, OF MOSCOW, RUSSIA.

VERTICAL CENTRIFUGAL PUMP.

1,185,508.

Specification of Letters Patent. Patented May 30, 1916.

Application filed January 12, 1915. Serial No. 1,797.

To all whom it may concern:

Be it known that I, BASIL KAMENSKI, a subject of the Czar of Russia, residing at 19 Trubnikovski Pereulok, Moscow, Russia, 5 have invented certain new and useful Improvements in Vertical Centrifugal Pumps, of which the following is a specification.

This invention relates to a centrifugal pump having a vertical axis, and in which 10 the level of the fluid in the pump casing is maintained at a constant height by means of a float controlled device.

The action of my pump is based upon the mechanical law according to which the 15 centrifugal force exerted by a rotating fluid particle is proportional to its distance from the axis of rotation of the fluid. Thus, when the liquid in the case is brought into rotation the centrifugal force gradually increases from the axis of rotation to the periphery of the liquid and thus causes the liquid to rise to a higher level at the periphery than at the axis of rotation, the surface 20 of the liquid between the highest and lowest 25 levels forming approximately a curve having the shape of a parabola. The fluid pressure at the axis is a minimum, and the pressure at the sides is a maximum.

My invention is illustrated by the accompanying drawing, in which:

Figure 1 shows a section through the float chamber and the pump casing; and Fig. 2 shows a similar section through a modified form of apparatus.

In Fig. 1, the pump consists of a case 1, provided with a vertical axis 3, having 35 blades or an impeller 2. The axis 3 is provided with a pulley 4 which can be rotated by any suitable means from a motor. In 40 the middle of the bottom of the case 1, a pipe or channel 8 is arranged communicating with the vessel 5 containing a float 9, and on the outer side of the case 1 a pipe 7 is arranged for the purpose of discharging

45 the fluid from the pump. When the impeller 2 begins to rotate, the fluid flows through the pipe 7, and the quantity of fluid removed is replaced from the reservoir 5 controlled by the floating device 9. The 50 fluid level at the axis 3 in the case 1, that is, the lowest point of the curve, will be maintained at the same height by means of the float controlled device in the vessel 5.

The liquid may be supplied either through 55 the top or the bottom of the vessel contain-

ing the float, but preferably through the opening 6¹ in the bottom thereof.

By having a closed top to the pump casing, the outer portion of the liquid contained in said casing will be prevented from 60 rising upward in parabolic form, as would occur if the top of the casing were open, and an air space will be left in the center of the casing beneath the central portion of the cover of the casing, as shown in dotted lines 65 in Fig. 1. By this arrangement of having a constant level of the liquid in the float chamber a delivery of the liquid through the pipe 7 may be secured at a rate dependent upon the speed of revolution of the impeller blades, without the well known disturbing factors where the pressure of the incoming liquid varies, etc. Under these 70 conditions, the following theoretical conclusions would substantially prevail. 75

If the velocity of the discharge through the outlet 7 is represented as v ; and the height of the fluid at the periphery and accordingly the pressure of the fluid, as h ; and the force due to gravity as g ; then the 80 height h of the fluid is expressed

$$h = \frac{v^2}{2g}.$$

The velocity of the discharge through the 85 outlet 7 at the side of the case 1 will equal

$$v = \sqrt{2gh};$$

that is, h being proportional to the square 90 of the number of revolutions, the quantity of fluid discharged by the pump is proportional to the number of revolutions of the fluid.

In order to obtain such a technical effect 95 the fluid level in the pump casing must be maintained at the same height, and the pump must have a vertical direction. My invention offers an apparatus complying with both these requirements.

Fig. 2 shows a modification in construction of the pump, in which the pump casing includes, also, the chamber containing the float and the impeller blades rotated about this inner chamber as shown. The 100 operation is otherwise the same as with the structure shown in Fig. 1.

In the form of device shown in Fig. 1, there is an upper valve 12 carried by the float, which closes when the float rises and thus cuts off the supply of incoming liquid, 110

and there is also a valve 12^a which closes of its own weight when the float rises, so that liquid which would be supplied through the openings 6 and 6¹ only enters the chamber 5 when the float is below a predetermined height.

In the form of device shown in Fig. 2, there is a single valve 12^a which is closed by the levers 11 as the float rises and opens 10 as the float falls.

I do not claim any special means of controlling the admission of fluid by means of the float, as a great variety of such means may be adopted if desired.

15 It will be seen that the level of the liquid in the float chamber is located in a horizontal plane between the upper and lower limits of the impeller blades, and that there will normally be an air space in the upper 20 portion of both the pump casing and the float chamber.

Having thus described my invention what I claim and desire to secure by Letters Patent of the United States is:—

25 1. In a pumping apparatus of the character described, the combination with a source of liquid supply, and means for maintaining the liquid therein at a predetermined level, of a pump casing connected to said

source of liquid supply, a centrifugal impeller having a vertical axis mounted in said casing, said impeller having blades projecting above and below the level of the liquid in the source of liquid supply, and an outlet from the periphery of said casing 35 for conveying the liquid therefrom, substantially as described.

2. In a pumping apparatus of the character described, the combination with a source of liquid supply, and a float and valve 40 mechanism operated thereby for maintaining the liquid therein at a predetermined level, of a pump casing connected to said source of liquid supply, a centrifugal impeller having a vertical axis mounted in said 45 casing, said impeller having blades projecting above and below the level of the liquid in the source of liquid supply, and an outlet from the periphery of said casing for conveying the liquid therefrom, substantially as described.

50 In testimony whereof I affix my signature in presence of two witnesses.

BASIL KAMENSKI.
